UNITED STATES PATENT OFFICE.

JOSEPH H. BRISKIN, OF LOS ANGELES, CALIFORNIA.

FORMING MACHINE.

Application filed April 4, 1922. Serial No. 549,531.

To all whom it may concern:

Be it known that I, JOSEPH H. BRISKIN, a citizen of the United States, residing at Los Angeles, California, have invented a certain new and useful Forming Machine, of which the following is a specification.

My object is to make a forming machine especially for making the water tube pieces of a radiator core, and my invention consists of the novel features herein shown, described and claimed.

A leading feature of my invention consists of the combination of a reel adapted to receive a reel of stock, an adjustable gage 15 to receive the stock from the reel, corrugating rolls which pull the stock from the reel through the gage and push the corrugated stock forwardly to be finished, adjustable center finishing dies, and adjustable side finishing dies.

Another leading feature consists of adjustable reciprocating finishing dies, so that stock of various widths may be readily used.

Another leading feature consists of connecting reciprocating finishing dies to corrugating rolls, so as to take stock from a roll, corrugate the stock, and feed the corrugated stock to the finishing dies.

In the drawings:

30 Fig. 1 is a side elevation of a forming machine for making the water tube pieces of a radiator core in accordance with the principles of my invention, parts being broken away and shown in section.

35 Fig. 2 is an enlarged fragmentary sectional detail of the corrugating rolls.

Fig. 3 is a fragmentary sectional perspective detail of the adjustable gage, the section being taken on the line 3—3 of Fig. 1.

40 Fig. 4 is a top plan of the lower adjustable center finishing dies and the adjustable side finishing dies.

Fig. 5 is a bottom plan of the dies shown in Fig. 4.

45 Fig. 6 is a cross section on the line 6—6 of Fig. 4.

Fig. 7 is a cross section on the line 7—7 of Fig. 4.

50 Fig. 8 is a fragmentary perspective of a part of the lower side finishing dies.

Fig. 9 is a bottom or face plan of the upper center finishing and the upper side finishing dies matching the dies shown in Fig. 4.

55 Fig. 10 is a top or back face plan of the dies shown in Fig. 9.

Fig. 11 is a fragmentary detail perspective of the upper side finishing dies matching the dies shown in Fig. 8.

Fig. 12 is a side elevation of the center and the side finishing dies in operative relation.

Fig. 13 is a fragmentary perspective of a piece formed by the machine and adapted to serve as a part of a water tube of a radiator core.

Fig. 14 is a vertical sectional detail showing how two pieces fit together to form a water tube.

Fig. 15 is an edge view of the water tube as indicated by the arrow 15 in Fig. 14.

Fig. 16 is a fragmentary cross section on the line 16—16 of Fig. 14.

Fig. 17 is a fragmentary detail looking at the opposite side of the machine from Fig. 1 and showing only the brake construction.

Referring to the drawings in detail:

The forming machine is built upon a punch press having a base 1, a bed 2, uprights 3 and 4, a head 5, a slide 6, a crank 7, and a fly wheel 8, all of the ordinary construction.

A supporting plate 9 fits between the lower ends of the uprights 3 and 4 and is secured in place by cap screws 10 inserted upwardly through the extension 11 of the bed 2. Bearings 12 extend backwardly and downwardly from the plate 9, a shaft 13 is mounted in the bearings 12, housing blocks 14 extend upwardly from the bearings 12, and the supporting arms 15 and 16 extend backwardly from the junction of the bearings 12 and housing blocks 14.

The reel 17 is a shaft mounted loosely through the rear ends of the supporting arms 15 and 16 and a roller on the shaft, and the roll 18 of radiator metal is mounted upon the reel.

The adjustable gage 19 consists of the following details:

The lower plate 20 has its sides bent downwardly to fit between the arms 15 and 16; the upper plate 21 has its sides bent upwardly and the back gage plate 22 fits between the back sides of the plates 20 and 21, and rivets 23 hold the three pieces together. The upper plate 21 has openings 24 through which the stock 18 can be seen. The down and up turned ends of the plates 20 and 21 are secured to the arms 15 and 16 by screws. The adjustable front gage

plate 25 slides through a slot in the arm 16 between the plates 20 and 21 and has an up turned outer end to serve as a handle 26. Spaced screw holes 27 are formed 5 through the plates 20 and 21 and nuts 28 are soldered against the lower face of the plate 20 in line with the screw holes. The gage plate 25 has holes near its inner edge and screws 29 are removably inserted downwardly through the parts into the nuts 28. The stock 18 is inserted between the plates 20 and 21 against the back gage 22, the front gage 25 is moved against the stock and the screws inserted and tightened to 15 pull the plates together. By moving the screws the gage is adjusted to different widths of stock, and the gage causes the stock to run straight from the reel to the corrugating rolls.

20 The details of the corrugating rolls 30 are as follows:

A roll 31 is fixed upon the shaft 13 between the bearings 12. Springs 32 are mounted in the housing blocks 14, bearings 25 33 are slidingly mounted in the housing blocks 14 against the springs 32, a shaft 34 is mounted in the bearings 33, and a roll 35 is mounted upon the shaft 34 between the housing blocks and in line with the roll 31.

30 The bearings 33 slide up and down and the springs 32 are under the bearings and serve to move the roll 35 upwardly away from the roll 31. Caps 36 are removably mounted upon the housing blocks and adjustably operated screws 37 are inserted downwardly through the caps against the bearings 33, so that by manipulating the screws 37 the roll 35 is adjusted to or from the roll 31.

40 The rolls 31 and 35, as shown, have matching teeth 38 and grooves 39. At the point of each tooth 38 is a punch seat 40 and at the bottom of each groove is a punen 41 to match the punch seat. The punch seats 40 and punches 41 are used in making the air cooling spacer pieces of the radiator core, but are not used in making the water tube pieces set up in this case. The spacer pieces are made on the same machine by 45 changing the dies. When it is desired to make the water tube pieces, the screws 37 are manipulated to move the roll 35 away from the roll 31 until the punches 41 are out of operative relation with the punch seats 40 and then the rolls simply corrugate the stock and draw it from the reel 17 through the gage 19 and push it on to the finishing dies. The flat stock 18 passing through the rolls 30 becomes the corrugated 50 stock 42 and this runs over the spring stripper 43, which is a plate pivoted at its rear end and has a spring 44 under its forward end, so as to run the stock over the lower finishing dies and allow the stock to be 55 pressed down into the dies and the tension

of the spring 44 raises the stock out of the dies for the next movement.

The corrugated stock 42 passes between the lower center finishing dies 45 and the upper center finishing dies 46, then between 70 the lower side finishing dies 47 and the upper side finishing dies 48, then over the spring stripper 49 which is similar to the stripper 43, and then over the curved guide plate 50.

The details of the center finishing dies 45 and 46 and the side finishing dies 47 and 48 are as follows:

The lower finishing dies 45 and 47 are assembled together and mounted on the 80 bolster plate 51 and the bolster plate is mounted on the bed 2. A dove tail slide way or seat 52 is formed in the upper face of the bolster plate 51 and the dove tail anchor plates 53 and 54 fit in the seat 52. Vertical longitudinal slots 55 and 56 are formed in the anchor plates from their outer 90 ends and near their front sides and screw holes 57 and 58 are formed near the outer ends of the slots, the upper ends of the holes being countersunk. Screws 59 are inserted downwardly into the holes 57 and 58 and have tapered shoulders just below their heads to fit the countersinks, and the screws are short, so that when the anchor plates 95 are placed in proper positions in the seat 52, the screws 59 are tightened thus expanding the anchor plates and holding them rigid upon the bolster plate. The side bar die plates 60 and 61 are secured against the inner ends of the anchor plates 53 and 54 by countersunk cap screws 62. The extension bar 63 is recessed into the lower faces of the anchor plate 54 and side bar 61 and held rigid by screws or rivets. A recess 64 is formed in the lower faces of the anchor plate 53 and side bar 60 to receive the extension bar 63 so that the side bar 61 may be moved toward or away from the side bar 60. The intermediate die plates 65, 66, 67 100 and 68 are recessed in their lower faces to fit upon the bar 63 and fit closely side by side and against the inner faces of the rear halves of the side bars 60 and 61. Rods 69 and 70 are inserted through all the parts 105 parallel with the bar 63. The yielding die plates 71 and 72 fit against the inner faces of the front halves of the side bars 60 and 61. Stud bolts 73 and 74 are inserted through vertical slots in the plates 71 and 72 into the side bars 60 and 61. Spring seat plates 75 and 76 are recessed into the lower faces of the bars 60 and 61 and extend under the ends of the die plates 71 and 72 and springs 77 and 78 fit between the plates 110 75 and 76 and the die plates 71 and 72.

The die plates 65, 66, 67 and 68 and the corresponding portions of the die plates 60 and 61 constitute the lower adjustable center finishing dies 45, and the die plates 71 115

and 72 and the corresponding portions of the die plates 60 and 61 constitute the lower side finishing dies 47. The adjustment is made by putting in or taking out one or 5 more of the die plates 65, 66, 67 and 68, and moving the anchor plates 54 and 53 towards or away from each other. The die plates 65, 66, 67 and 68 are made in various widths so as to secure any desired adjustment. 10

The upper finishing dies 46 and 48 are shaped and adjusted to match the lower finishing dies 45 and 47. The anchor plates 79 and 80 have dove tail seats 81 and 82 in their upper faces and the dove tail 83 of the punch plate 84 fits in the seats. The extension bar 85 is secured against the lower face of the anchor plate 80 and fits slidingly against the lower face of the anchor plate 79. The side bar die plates 86 and 87 are secured against the lower faces of the anchor plates 79 and 80 by screws 88 and 89 and have recesses to receive the bar 85. The intermediate die plates 90, 91, 92 and 93 are recessed to slide upon the bar 85 and match the bars 65, 66, 67 and 68. Rods 94 and 95 are inserted through all the die plates parallel with the bar 85. The yielding die plates 96 and 97 are connected to the side bars 86 and 87 in the same manner as the die plates 71 and 72. The anchor plates 79 and 80 are held in place by set screws 98.

The corrugations of the stock 42 are regular half round curves up and down and the center finishing dies 45 and 46 sharpen the up curves to produce the ribs 99 to engage the air cooling spacer piece of the radiator core. The edges 100 of the lower dies engage in the sharp grooves 101 of the upper dies. 25 The spacing of the dies are the same as the spacing of the corrugating rolls. The side finishing dies 47 and 48 reform the edges of the stock to produce the flat longitudinally extending faces 102 in line with the ribs 99, 40 the longitudinally extending flat faces 103 in line with the curves 104 between the ribs 99, and the inclined flat faces 105 connecting the faces 102 and 103. The faces 102 are drawn down slightly relative to the ribs 99 45 and the faces 103 are drawn down considerably relative to the curves 104, so that when the pieces are placed together bottom to bottom the faces 102, 103 and 105 fit close together and form an edge 106 with the ribs 99 projecting longitudinally outwardly 50 alternately from opposite sides and between the edges the water space 107 is formed.

The yielding die plates 71 and 72 and 96 and 97 normally project above the rigid die plates and may rock slightly and serve to register the stock accurately in the dies before the final action.

The anchor plates 54 and 80 are set so as to bring the outer sides of the die plates 61 65 and 86 in line with the back gage 22, then

the intermediate dies 65, 66, 67 and 68 and 90, 91, 92 and 93 are applied to make the proper width and the anchor plates 53 and 79 applied. When the width of stock is changed the intermediate dies are changed 78 accordingly.

A guide flange 108 is mounted upon the guide plate 50 in line with the back gage 22 and an adjustable guide flange 109 is mounted upon the guide plate to engage the front 75 edge of the stock, so that the stock will run straight through the machine.

An adjustable brake construction 110 is applied to the rear end of the shaft 13 so as to hold the corrugating rolls from spinning. 80 A brake wheel A¹ is fixed on the shaft 13. An angle bracket A is secured to the supporting arm 15 by bolts B. The brake band has a circular portion C fitting the wheel A¹, an end portion D secured to the bracket A by a bolt E, and an end portion F parallel with the portion D. A bolt G connects the portions D and F so as to adjust the tension of the portion C upon the wheel A¹. 85

The details of the step-by-step connection between the rotary corrugating rolls 30 and the reciprocating finishing dies are as follows:

A ratchet wheel 111 is fixed upon the shaft 13 in front of the front bearing 12 and has the same number of ratchet teeth 112 as the roll 31 has teeth. A crank 113 is loosely mounted upon the shaft 13 and carries a pawl 114 to engage the teeth 112. An adjustable pitman rod 115 is connected to the crank 113. A crank 116 is fixed upon the front end of the crank shaft 7. A head 117 is adjustably mounted upon the crank 116 and connected to the pitman rod 115, so that as the crank shaft 7 rotates the pawl 114 reciprocates to drive the corrugating rolls a step at each operation of the reciprocating dies, so as to advance the stock regularly step-by-step. The head 117 is adjustable so as to vary the stroke of the pawl 114 105 to take more or less teeth 112 at a step. 110

I prefer to advance the stock the amount of three teeth 112 at each operation, but the parts may be assembled and adjusted for more or less advancement by means of the 115 adjustable head 117 on the crank 116.

Thus I have produced a machine which takes metal from a roll and progressively and continuously forms the water tube pieces of a radiator core, and which may be 120 readily adjusted to use metal of various widths.

Various changes may be made without departing from the spirit of my invention as claimed. 125

I claim:

1. A forming machine comprising a reel adapted to receive a roll of metal, an adjustable gage in front of the reel and through which the metal passes, corrugating rolls in 130

- front of the gage and adapted to pull the metal from the reel through the gage, adjustable center finishing dies in front of the corrugating rolls, adjustable side finishing dies in front of the center finishing dies, and a connection between the rotary corrugating rolls and the reciprocating finishing dies whereby the corrugating rolls feed the corrugated metal to the finishing dies.
- 10 2. A forming machine comprising means including corrugating rolls for withdrawing sheet metal from a source of supply and corrugating it, in combination with means including dies adapted to deform the center 50 of the corrugations thus formed in one manner and deform the ends of the corrugations in a different manner, both of said means being connected together by a step-by-step mechanism.
- 15 3. A deforming machine comprising means including corrugating rolls for withdrawing sheet metal from a source of supply and corrugating it, in combination with means including adjustable reciprocating 55 dies adapted to deform the center of the corrugations thus formed in one manner and deform the ends of the corrugations in a different manner.
- 20 4. A forming machine comprising means including a pair of corrugating rolls for withdrawing sheet metal from a source of supply and corrugating it, means including reciprocating dies connected to said corrugating rolls by a step-by-step mechanism for 60 deforming the corrugations formed by said corrugating rolls, said dies including adjustable center finishing dies for deforming the centers of said corrugations in one manner, and side finishing dies for deforming 65 said corrugations in a different manner.
- 25 5. A forming machine comprising means including a pair of corrugating rolls for withdrawing sheet metal from a source of supply and corrugating it, means including reciprocating dies connected to said corrugating rolls by a step-by-step mechanism for deforming the corrugations formed by said corrugating rolls, said dies including center 70 finishing dies adapted to deform the centers of said corrugations in one manner and adjustable side finishing dies for deforming the ends of said corrugations in a different manner.
- 30 6. A forming machine comprising means including a pair of corrugating rolls for withdrawing sheet metal from a source of supply and corrugating it, in combination with means including reciprocating dies for deforming the corrugations formed by said corrugating rolls, said dies including adjustable center 75 finishing dies and adjustable side finishing dies associated with said center finishing dies, said side finishing dies being adapted to deform said corrugations in a different manner from the center finishing dies.
- 35 7. In a forming machine, a frame, a corrugating roll rotatably mounted upon said frame, bearing blocks slidable upon said frame, a second corrugating roll mounted between said bearing blocks, the top of each tooth on said corrugating rolls being provided with a recess and the bottom of the recess between each tooth being provided with a punch point adapted to enter the recess in each tooth upon the opposite roll, 80 and means for adjusting said second corrugating roll whereby said punch points may be caused to enter their corresponding recesses to punch the material passed between the corrugating rolls or said punch points may be caused to remain out of their corresponding recesses so that the material may be merely corrugated.
- 40 8. In a forming machine, a die comprising a pair of anchor plates, side bar die plates secured to said anchor plates, an extension bar secured to one anchor plate and slidable upon the other, removable intermediate die plates positioned upon said extension bar and secured together between said side bar die plates adjacent the rear end thereof, and yieldable die plates secured against the inner faces of said side bar die plates adjacent the front thereof.
- 45 In testimony whereof I have signed my name to this specification.

JOSEPH H. BRISKIN.
